M. FRANKLE

NONVIBRATORY VENTILATOR CLOSURE

Filed March 19, 1925

Patented Dec. 8, 1925.

1,564,412

UNITED STATES PATENT OFFICE.

MILTON FRANKLE, OF DES MOINES, IOWA.

NONVIBRATORY VENTILATOR CLOSURE.

Application filed March 19, 1925. Serial No. 16,814.

To all whom it may concern:

Be it known that I, MILTON FRANKLE, a citizen of the United States, residing at Des Moines, in the county of Polk and State of Iowa, have invented certain new and useful Improvements in a Nonvibratory Ventilator Closure, of which the following is a specification.

This invention relates to an improved 10 ventilator for the cowls or hoods of automobiles generally, and particularly for the Ford type of automobiles, and has for its principal objects to provide such a construction that, upon closure of the lid, air will 15 be effectively prevented from moving through the ventilator, and that vibration occasioned by the lid will be prevented.

With the foregoing objects in view the invention presents a novel and useful construction, combination and arrangement of 20 parts as described herein and claimed, and as illustrated in the accompanying drawing, it being understood that changes in form, size, proportion and minor details may be 25 made, as found to be of advantage, said changes being determined by the scope of the invention as claimed.

In the drawing, Fig. 1 shows a side view 30 of the front part of an automobile provided with a ventilator. Fig. 2 is a plan view of an elastic, endless ring or band. Fig. 3 is a plan view, partly in section, of a ventilator constructed in accordance with the invention. Fig. 4 is a transverse section through the ventilator on line 4—4 of Fig. 3, also showing the ventilator attached 35 to the hood or cowl, the lid being closed. Fig. 5 is a similar sectional view of parts to that shown in Fig. 4, the lid being swung to 40 open position.

Referring now particularly to the drawing, the invention is shown and described in connection with the cowl or hood 6 of an automobile, said cowl being provided with 45 an aperture 7 communicating with the interior of the vehicle. The ventilator consists of an endless, upright, grooved collar 8 provided with an endless flange 9 of approximately rectangular form in plan, said flange being adapted to be disposed outwardly of the margin of the aperture 7 and to be secured to the cowl or hood forwardly 50 of the vehicle body 10.

At 11 is indicated a lid mounted to permit swinging movements, as indicated at 12, from the rear part of the flange 9, said lid

being provided with parallel wings 13 which project inwardly of the hood to control the direction of movement of air entering the ventilator from the atmosphere. 60

Numeral 14 indicates a handle or pull-and-push-bar for the use of an operator who, while occupying the driver's seat, may manually raise the lid to the position shown in Fig. 1 or Fig. 5, or may cause the lid to 65 swing downwardly to the position shown in Figs. 3 or 4.

In order that vibration will be prevented which otherwise might be caused by the 70 intermittent engagement of the lid with its metallic support, and that a complete closure may be made of the ventilator, I provide an endless, elastic ring or band, circular in cross-section, adapted to be disposed in the groove α of the collar. 75

By referring to Figs. 4 and 5 of the drawing it will be seen that the outer side of the collar is concaved. The band or ring 15 should be elastic, and preferably is constructed of hollow india-rubber tubing, and is of such proportion that it will fill and that a material and considerable proportion thereof will project outwardly of the groove α , said outwardly projecting part of the 80 ring being an important feature in operation; and when the lid is lowered to a closed position the lip or endless flange 16 of the lid will engage the ring to prevent any movement of air through the ventilator and to 85 prevent vibration which otherwise would be occasioned by intermittent unequal or incomplete engagement of said lip or flange 16 with the collar. The band or ring 15 normally is of somewhat less circumference 90 than the grooved collar and must be stretched and elongated somewhat to mount it on the collar, after which its tension tends to hold it in place, without the aid of any securing means. 95

In the construction of ventilators for the 100 cowls of motor vehicles, the mounting of the lid is sufficiently loose to permit it to be readily elevated or lowered manually whenever required, and therefore the metallic parts, when the lid is lowered, are subject to vibration unless an elastic filler is provided; but by use of the elastic ring, as described, all noise occasioned by vibration 105 will be eliminated. Also in cold weather it is desirable that no air shall enter the automobile through the ventilator, and since the ring projects outwardly of the collar it will 110

be engaged by the lip or flange of the lid, when said lid has been swung downwardly, which effectively prevents said air from entering. The ring when so mounted and 5 engaged by the flange of the lid also prevents rattling by lateral as well as up and down movement.

I claim as my invention,—

1. In a ventilator closure, the combination with the cowl at the front part of an automobile, said cowl being provided with an aperture, and a collar having an upright, laterally grooved wall and mounted on the cowl outwardly of the margin of said aperture, of an elastic ring removably mounted in said groove and held therein by its inherent elasticity, and a hingeably mounted lid having a downwardly projecting, endless flange and adapted to be swung downwardly 10 to dispose its flange outwardly of said groove into close engagement with the outer circumferential side of said elastic ring, to prevent admission of air and the rattling of the closure by either lateral or vertical movement of the flange against the collar.
2. In a ventilator closure, the combination with an apertured cowl and an upright collar provided with an endless groove on its outer lateral face and having a flange, said 15 collar being adapted to be disposed above the flange with said flange secured to that part of the cowl outwardly of the margin of said aperture, of an endless, elastic ring normally circular in cross-section and of less 20 annulus than the top margin of said collar

and adapted to be removably disposed within the groove and held therein by tension and to project outwardly of the collar, and a lid having a downwardly projecting, endless flange and adapted to be moved downwardly 40 to dispose its flange into close engagement with the outer circumferential side of said ring to prevent admission of air and the rattling of the closure by either lateral or vertical movement of the flange against the 45 collar.

3. In a ventilator closure, in combination, a cowl having an aperture, an upright collar provided with an endless lateral groove and having an endless flange adapted to be 50 secured to the cowl outwardly of the margin of said aperture, a lid having a downwardly projecting, endless flange and adapted to be moved downwardly to dispose its endless flange outwardly of the endless groove of 55 the collar, and a hollow endless, flexible ring normally circular in cross section and adapted to be removably disposed with a part engaging and held by tension within said groove and with a part projecting outwardly a material and considerable distance from said endless groove for closely engaging the endless flange of said lid to prevent admission of air and the rattling of the closure by either lateral or vertical movement of the flange against the collar.

In testimony whereof, I have affixed my signature.

MILTON FRANKLE.
